United States Patent Office

Des. 186,120
Patented Sept. 15, 1959

186,120

PUPPET DOLL OR SIMILAR ARTICLE

James M. Henson, Hyattsville, Md., and Jane A. Nebel,
Washington, D.C., assignors to John H. Wilkins Company, Washington, D.C., a corporation of Delaware

Application October 17, 1958, Serial No. 53,013

Term of patent 14 years

(Cl. D34—4)

Des. 186,120

Figure 2 is a side elevational view of the puppet doll or similar article shown in Figure 1 (the side elevation being the same from either side).

We claim:

The ornamental design for a puppet doll or similar article, substantially as shown and described.
